(57) **CLAIM**

I claim the ornamental design for a flexible collapsible protective sleeve for medical tubing, as shown and described.

DESCRIPTION

FIG. 1 is a side elevational view of the flexible collapsible protective sleeve for medical tubing, showing my design.

FIG. 2 is a front elevational view thereof.

FIG. 3 is a rear elevational view thereof; and,

FIG. 4 is a side elevational view thereof in an expanded form.

The broken-line showing of a medical tube in FIGS. 1 and 4 illustrates environmental matter and forms no part of the claimed design.
